(57) **CLAIM**

The ornamental design for the pen with magnetic cap, as shown and described.

DESCRIPTION

FIG. 1 is an exploded top perspective view of a pen with magnetic cap showing my new design;

FIG. 2 is an exploded side elevational view of FIG. 1;
FIG. 3 is an exploded bottom perspective view thereof from the opposite end of FIG. 1;

FIG. 4 is a top plan view of FIG. 1;

FIG. 5 is a bottom plan view of FIG. 1;

FIG. 6 is a closed top perspective view of FIG. 1;

FIG. 7 is a closed side elevational view of FIG. 1;

FIG. 8 is a side elevational view of FIG. 3 with the cap attached;

FIG. 9 is a top plan view of FIG. 8; and,

FIG. 10 is a bottom plan view of FIG. 8.
